UNITED STATES PATENT OFFICE.

STANLEY G. WISE, OF DAYTON, OHIO, ASSIGNOR TO THE GEBHART FOLDING BOX COMPANY, OF DAYTON, OHIO, A CORPORATION OF OHIO.

FOLDING BOX.

Application filed June 21, 1926. Serial No. 117,336.

My invention relates to folding boxes and in particular to a box which, when unfolded, will assume an unfolded condition with the end walls and side walls of equal height.

Heretofore, it has been regarded as impossible and as being unknown in the trade to have a box which may be moved from a partially folded condition in flat shape to a fully folded and assembled condition, in which the side walls of the box are of the same height as the end walls.

It is my object to provide a box which may be shipped in semi-folded condition in flat form and which can be easily assembled into fully assembled condition by simple movements of any unskilled person.

Referring to the drawings:

Figure 1 is a plan view of the top of the box in semi-folded condition ready for shipment in its flat form;

Figure 2 is a similar view showing the side wall flaps in unfolded position for the purpose of illustration;

Figure 3 is a section on the line 3-3 of Figure 1;

Figure 4 is a side elevation of the box just as it is being assembled into its fully unfolded and assembled condition;

Figure 5 is a section on the line 5-5 of Figure 4;

Figure 6 is a side elevation of the box in fully assembled and unfolded condition;

Fig. 7 is a view of the blank;

Fig. 8 is a perspective view of the box in assembled expanded position.

Referring to the drawings in detail, 1 designates the bottom of the box which is provided with end walls 2 and 3 and side walls 4 and 5. The end walls are turned over at their outer ends into flaps 6. The end walls are turned over at their sides so that there is an overlapping side flap 7, which lies beneath the end flap 6. Staples 8 are placed therethrough. There are similar overlapping side flaps 7 which overlap each other at their inner corners 7a. These side flaps are connected integrally with intermediate flaps 9 which are substantially triangular in shape. These intermediate flaps are connected to the side flaps 7 along a scored hinge 10. They are provided with free diagonal edges 11 which form the second side of the triangle while the third or vertical side of the triangle is formed by the score 12 along which line the intermediate flap is

joined to the respective side walls 4 or 5. The side walls 4 or 5 are formed with an inwardly folding side wall flap 13 which is folded along the scored line 14 which proceeds parallel to the top edge 15 of the side wall crossing the scores 12 and across the upper parts of the intermediate flaps, terminating at the edges 11 of the intermediate flaps. Thus, the side wall flap and the top of the intermediate flaps are adapted to fold inwardly. This permits of the side walls being folded as usual, but, when in unfolded condition permits of their full expansion and the side walls being of the same height as the end walls and the bottom width. When the box is expanded and opened up into its folded form to make a box complete, it will be noted that the overlapping intermediate flaps gradually assume a vertical position parallel to the inside of the end walls 2 and 3, while the side walls assume a vertical position and the flaps are unfolded, as in Figure 5 and Figure 6.

It will be understood that I desire to comprehend within my invention such modifications as may be necessary to adapt it to varying conditions and uses.

Having thus fully described my invention, what I claim as new and desire to secure by Letters Patent, is:

1. In a collapsible box adapted to be arranged in semi-folded flat form and to be moved from that form into fully assembled form, the combination of a bottom, end walls and side walls, said end walls and side walls when in fully assembled form being of the same height, equal to the width of the bottom, said side walls being folded upon themselves when the box is in collapsed condition.

2. In combination in a box, of a bottom, end walls and side walls, said side walls when in collapsed condition having upper portions folded upon each other and so arranged that the box may be assembled in flat form and may be automatically unfolded from the assembled flat form to the assembled set-up condition with the side walls and end walls of the same height, equal to the width of the bottom.

3. In combination in a box, a bottom, end walls and side walls, side flaps attached to the end walls and intermediate flaps connected to the side walls and to the side flaps, said side walls being creased and the outer

portions folded back onto the main portions thereof when the box is arranged in semi-folded flat form.

4. In combination in a box of a bottom portion, end wall portions, end flaps on the end wall portions, side wall portions composed of main side wall portions, intermediate flap portions and side flap portions, said side flap portions being adapted to fold over each other beneath the end flaps of the end walls, means to fasten said end flaps to the side flaps and end walls, said parts being so arranged that they may be folded in a collapsed position flat and moved from the collapsed position to a fully expanded position with the intermediate flaps parallel to the end wall portions and at right angles to the main side wall portions, said side walls having portions adapted to be folded when the box is in semi-folded collapsed position and extended in line with the main side wall portions when the box is in expanded position, the height of the end walls and side walls being equal to the width of the bottom.
5. In combination in a box adapted to be arranged in flat form in semi-assembled condition and moved from that condition to fully assembled condition automatically, a box blank having an integral bottom, hinged end walls, end flaps hinged on the end walls, hinged side walls consisting of main side wall portions, intermediate flap portions and side flap portions so arranged that when the box is in semi-folded flat condition the side flaps and side wall portions will be folded

parallel to the bottom and end wall portions, the side flaps will be overlapping and the end flaps overlapping the side flaps, while the intermediate flaps will overlap each other and the outer portions of the main side wall portions overlap each other, said main side wall portions having inwardly turned flaps along the upper edges adapted to be inwardly folded when the box is in flat condition and when said box is moved to an open condition, the main side wall flaps will be extended to form parts of the side walls.

6. In a one piece box, a blank having a bottom portion, end wall portions hinged thereto, end flap portions hinged to the end wall portions, side flap portions hinged to the sides of the end wall portions and hinged on their inner edges diagonally to intermediate flaps, intermediate flaps substantially triangular in shape having a free edge, main side wall portions having sides thereof hinged to the adjacent intermediate flaps and the bottom thereof hinged to the bottom portion of the blank, said intermediate portions and main side wall portions being creased parallel to the hinged line of the main side wall portion with the bottom portion to form a flap which is folded back against the intermediate and main side wall portions when the box is partially folded for shipment and extended when the box is set up ready for use.

In testimony whereof I affix my signature.

STANLEY G. WISE.
